SELF-LOCKING DEVICE FOR DISPLAY FRAMES
AND THE LIKE

Adrian P. Van Herk and Klaus Behnke, Willowdale, Ontario, Canada, assignors to Garsy Company of Canada Limited, Toronto, Ontario, Canada, a corporation of Canada

Filed Sept. 30, 1964, Ser. No. 400,349
1 Claim. (Cl. 287—56)

ABSTRACT OF THE DISCLOSURE

The present disclosure comprises an elongated L-shaped lever with a broad body and at the apex or juncture of the arms of the body is formed with a thick portion and projecting laterally from the sides of the thick portion there are a pair of opposed trunnions for pivoting the lever on opposed supports. This construction permits the lever to be mounted pivotally on a base in the path of movement of an insertable structural member such as a post so that the lever is pivoted and its short arm bites into the post during insertion and its long arm swings under the post so that the post is pressed laterally against a pair of spaced points of support.

This invention relates to improvements in a self-locking device for display frames and the like and appertains particularly to such a mechanism that is suitable for rigidly securing vertical members to their horizontal base supports.

In assembling preformed metal display frames, it is essential that the gondola posts or uprights be rigidly mounted in true vertical and parallel relation. If the structure be of a knockdown or demountable nature, nuts and bolts are frequently employed and the bolt accommodating perforations must first be carefully positioned in registry, all of which consumes time and the eventual assembly not infrequently allows of some looseness.

It is an object of our present invention to provide a self-locking mounting device for rigidly yet releasably holding an inserted upright member to a horizontal base member.

A further object of the invention is to provide a self-locking device for demountable display frames or the like that enables the easy and rapid assembly or dismantling of the parts without the use of any loose extraneous parts or requiring special tools or the employment of skilled workmen.

A further object of the invention is the provision of a self-locking mounting device that is rotatably carried by one member and brought into tight wedging relation with a second member on the engagement thereof by the second member as such second member is being applied to the first member.

A still further object of the invention is the provision of a simple, one-piece self-locking mounting device of the nature and for the purpose specified that is formable as an L-shaped or bell crank-like integer with trunnions projecting from opposite sides at the apex.

To the accomplishment of these and related objects as shall become apparent as the description proceeds, the invention resides in the construction, combination and arrangement of parts as shall be hereinafter more fully described, illustrated in the accompanying drawings, and pointed out in the claim hereunto appended.

The invention will be best understood and can be more clearly described when reference is had to the drawings forming a part of this disclosure wherein like characters indicate like parts throughout the several views.

2

In the drawings:

FIGURE 1 is a fragmentary side elevation of the lower portion of a display frame assembly showing an upright member secured to the horizontal base support member by our L-shaped self-locking mounting device;

FIGURE 2 is an enlarged side elevation of the L-shaped or bell crank-like locking device;

FIGURE 3 is an end elevation thereof; and

FIGURE 4 is a plan view thereof.

Referring now particularly to these drawings, the locking device, shown applied in FIGURE 1 and in detail in the remaining figures, will be seen to consist of an integral L-shaped or bell crank-like lever 5 of relatively wide flat form; the two arms of the L being disposed at right angles with the shorter arm 6 being about or less than half the length of the longer arm 7 or in the proportion of approximately 3:7 and for use with a 2 inch display frame upright, the arms would preferably be not more than $1\frac{1}{16}$ inches wide with a thickness of approximately $\frac{1}{4}$ inch or roughly one-sixth of the width.

Running along the outer side of the L-shaped lever 5 is a substantial centrally disposed rib 8 that tapers to the end of the short arm 6 at an angle of $65^\circ \pm 5^\circ$ to the vertical end of the arm and to the horizontal end of the longer arm 7 at an angle of $45^\circ \pm 5^\circ$.

The junction 9 of the arms 6 and 7 of the L-shaped lever may be rounded on the outer side and the rib 8 as it continues therepast is likewise of arcuate contour, as seen best in FIGURE 2.

On the inner face of the junction 9, which may be referred to as the apex, the fulcrum is located, comprising a short stub shaft or trunnion 10 extending from opposite edges of the L-shaped or bell crank lever 5, being external projections of a transverse thickening 11 at the apex.

In the present case, the illustrated locking lever 5 is employed in display frame assemblies, a typical application being shown in FIGURE 1 where a horizontally disposed foot or base part comprises a pair of laterally spaced horizontal members 20 whose upper and lower flanges 21 are directed outwardly allowing a clear vertical channel or canyon passage of say two inches or so in width for the reception therebetween of a vertical post or upright member 22, shown as a hollow steel post of rectangular cross-section with an interiorly projecting rigidifying groove 23 up each side.

To assist in positioning the upright 22 in the canyon passage between the members 20 in the horizontal base, a pair of vertically spaced bolts 24 with appropriate nuts are used, traversing the base and serving also to secure these laterally spaced horizontal members 20 together.

Offset, or longitudinally spaced in the horizontal base, from these vertically spaced bolts 24 that act as abutments when engaged by the upright 22, the L-shaped lever 5 is rotatably mounted by its trunnions 10 journaled in the spaced horizontal members 20, and this occurs at a level intermediate of the vertical spaced abutments 24. The locking lever 5 is arranged with the L in inverted position and facing the abutments and so separated therefrom longitudinally of the horizontal base as to admit the rectangular upright 22 being dropped down between the bolts or abutments 24 on one side and the angle lever 5 on the opposite side, with the upright 22 sliding past the inturned short arm 6 until the bottom of the upright engages the longer arm 7 that projects across its path.

As the upright descends further it bears on the longer arm 7 causing the lever 5 to rotate on its trunnions 10 forcing the free end of the short arm 6 to jamb against the side of the upright opposite the abutments 24 and at a level intermediate said vertical spaced abutments. A tap as by a rubber mallet on the top of the upright fastens the same in sturdy rigid assembly with

the horizontal frame foot 20. While the free end of the longer arm 7 can be suitably rounded, it may be desirable to machine the biting free end of the shorter arm 6 to provide a sharp right angle face to engage the upright member.

If the horizontally disposed foot or base part of the display frame assembly and the vertical post be regarded as separable and intersecting members, it will be appreciated how simple and efficient a locking device the rotatably mounted right angle lever element is in having its longer arm coaxing with the lower end of the post so that its shorter arm is rotated into frictional engagement with the post on the side thereof opposite from that contacting the vertically spaced pair of abutments and at a level intermediate said abutments.

From the foregoing description taken in connection with the accompanying drawings, it will be manifest that a self-locking device suitable for knock-down display frames and the like is provided that will fulfill all the necessary requirements of such a device, but as many changes could be made in the above description and many apparently widely different embodiments of the invention may be constructed within the scope of the appended claim, without departing from the spirit or scope thereof, it is intended that all matters contained in the said accompanying specification and drawings shall be interpreted as illustrative and not in a limitative or restrictive sense.

What is claimed as new is:

An automatic locking device comprising in combination with two structural members, an angle-shaped lever pivotally attached at its apex to one structural member and normally hanging with one arm of the angle-shaped lever extending into the path of an being rotatable by

the other structural member, the second arm of said angle-shaped lever being pivoted into locked impingement with an adjacent wall of the other structural element by the engagement and continuing pressure on the first arm 5 of said angle-shaped lever by said other structural element, said first structural element having a vertically spaced pair of bolts acting as abutments and holding the plates together and said angle-shaped lever being pivotally attached to the same member in spaced relation to said 10 abutments and at a point intermediate said abutments, said one arm acting as a support for said other member and said second arm of the lever and said pair of abutments affording three clamping points for the other structural member, the arms of the angle-shaped lever being 15 of unequal length, and a transversely extending thickened portion on the inner face of the lever at its apex to act as trunnions and a centrally disposed rib extending along the other side of said lever having tapering end portions.
